AXEL WETTERVIK, OF IRON RIVER, MICHIGAN, ASSIGNOR OF ONE-HALF TO GUST
LINDAHL, OF IRON RIVER, MICHIGAN.

SNOW AND ICE MELTING MACHINE.

1,111,628.

Specification of Letters Patent. Patented Sept. 22, 1914.

Application filed August 5, 1913. Serial No. 783,056.

To all whom it may concern:

Be it known that I, AXEL WETTERVIK, a citizen of the United States, and a resident of Iron River, in the county of Iron and State of Michigan, have invented a new and Improved Snow and Ice Melting Machine, of which the following is a full, clear, and exact description.

This invention relates to a machine for melting snow and ice or for snow leveling and road making, and relates more particularly to a machine of that type including melting rollers containing the fire grates for holding the fuel whereby the cylindrical surface of the roller is heated for melting the snow and ice by direct contact therewith.

The invention has for its general object to improve and simplify the construction and operation of machines of this character so as to be reliable and efficient in use, and composed of comparatively few parts.

Another object of the invention is the provision of a snow and ice melting machine in which a plurality of melting rollers are mounted in frames mechanically connected together in such a manner that the machine can be readily steered.

Another object of the invention is the employment of a novel arrangement of doors at the ends of the rollers for permitting access thereto for inserting the fuel and removing the ashes and for controlling the draft.

With these objects in view, and others as will appear as the description proceeds, the invention comprises various novel features of construction and arrangement of parts which will be more fully described hereinafter and set forth with particularity in the claims appended hereto.

In the accompanying drawings, which illustrate one embodiment of the invention, and wherein similar reference characters are employed to designate corresponding parts throughout the several views, Figure 1 is a plan view of the machine with one roller in section and showing the rollers in full lines in position for straight ahead travel and in dotted lines in position for turning; Fig. 2 is a side view of the machine; Fig. 3 is a longitudinal section of the machine on a plane passing through one of the rollers; Fig. 4 is a transverse section taken in an axial plane of the rollers; Fig. 5 is an

end view of one of the rollers, showing the sectional door structure; and Fig. 6 is a side view of one of the sections of the door for the rollers.

Referring to the drawing, A and A' 60 designate the rollers of the machine which are mounted respectively in frames B and B'. Each frame consists of side members 1 and 2 and front and rear members 3 and 4, whereby a square or rectangular structure is formed, and projecting rearwardly from the corners of the frame are members 5 which terminate in a disk-shaped plate or fifth wheel structure 6. Between the plate 6 extends a connecting device C which 70 is shown in the form of a rigid box to which the plates 6 of the frames B and B' are hingedly connected by bolts 7 and 7', respectively. The box or connecting element C carries an upright steering post 8 which has 75 at its upper end a steering wheel 9 and on its lower end is a drum 10 or equivalent device, Fig. 3, around which passes a chain or other flexible element 11, the forward ends of the chain being connected at 12 with 80 the inner rear corners of the frames B and B', the purpose being that by turning the steering wheel 9 the chain 11 will cause the frames B and B' to swing in the same direction around their pivotal centers 7 and 7' 85 when the machine is to be turned to the right or left.

The two frames B and B' are slidably connected together by a central connecting element D, which has in its opposite sides, 90 as shown in Fig. 4, longitudinal guideways 13 with which the inner members 2 of the frames B and B' respectively engage. This connecting element D prevents the frames B and B' from spreading apart and 95 cooperates with the pivotal center 7 and 7' to always maintain the axes of the rollers A and A' in parallelism. On the side members 2 of the frames B and B' are flanges 100 or ribs 14, Fig. 4, which engage the flanges 15 of the guideways 13, so that the frames B and B' and connecting element D are securely fastened together while relative sliding movement longitudinally of the guideways is permitted. The front end of 105 the connecting element D is provided with a socket 16 for receiving a tongue or equivalent draft device 17, whereby the machine can be drawn by horses, although the machine may be used in connection with an 110

automobile, traction engine or the like. The frames B and B' are provided with forward extensions 18 on which are mounted boxes 19, which, like the box C, may be used for containing fuel or for any other purpose desired. It will be noted that each roller-carrying frame is provided with a box 19, while the box C is common to both sections of the machine. Each section of the machine is detachable from the box or connecting element C so that the sections may be used independently for melting snow or ice, and to provide for separation of the sections the frames B and B' are detachable from the connecting element D by a relative longitudinal movement of the bars. It will be noted that the guideways 13 extend the full length of the element D so as to permit the frames B and B' to be slipped into or out of their respective guideways. The element D may be held in place by a link or bar d uniting it with the box C. Each roller comprises a cylindrical body 20 formed as shown in Fig. 3 with spokes 21 that carry a central hub 22, and attached to each hub is an outwardly-extending stub axle 23 that is fastened in the adjacent side member of the roller-carrying frame B or B'. Within each roller is a fire-box E which loosely hangs on the inner ends of the axles or journals 23 and within each fire box is a grate 24 that supports the fuel. The ends of the rollers are provided with doors F which are preferably made of quadrant sections f of the form shown in Fig. 6, each section having a hub formed by a disk 25 suitably secured to the plate of which the section F is formed. The axle 23 passes through the openings 26 of the hubs of the door sections so that the latter will have a rotary movement about the axle 23 as a center. Extending outwardly from each section f is a handle or equivalent device 27 and the handles are so disposed on the respective sections that they will all lie above the frame B or B', as clearly shown in Fig. 2. Over each roller is a shield or guard G of suitable heat non-conducting material, and on the lateral edges of the guards are stops 28 with which the handles 27 of the door sections can be engaged for holding the doors in open or closed position. When the sections of the doors are in closed position, as shown in Fig. 2, the contiguous edges of adjacent sections overlap and form a complete closure for the end of the roller. When the door sections are to be moved to open position, as shown in Fig. 5, the upper two sections can be thrown downwardly and the lower sections thrown upwardly and held in such position by engaging their handles 27 with appropriate stops or hooks 28. In this way openings a, b are provided for permitting air to enter to the fuel and the products of combustion to discharge, the size of the

openings being regulated as desired. When the doors are fully opened the sections thereof overlap one another, whereby access to the interior of the roller is afforded.

As shown in Fig. 2, each side member of the frames B and B' is made in two parts separable on an inclined line 29 coincident with the axle 23 which is clamped between the two parts of the side of the frame, said parts being fastened together by bolts or equivalent devices 29a.

When the two sections of the machine are coupled together, as shown in Fig. 1, the driver uses the box C as a seat so that the steering wheel can be operated for steering the machine, but when one section of the machine is used separately the driver will sit on the front box 19. When using the machine the same is driven over the surface where the road is desired to be made, and by reason of the hot rollers the snow or ice will be melted, leaving a road through which traffic can be conducted.

From the foregoing description taken in connection with the accompanying drawings, the advantages of the method of operation and of the apparatus shown will be readily understood by those skilled in the art to which the invention appertains, and while I have described the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. In an ice and snow melting road making machine, a supporting frame, a roller mounted thereon and having open ends, a heating means in the roller, and draft controlling doors pivotally mounted on a common axis co-incident with the axis of the rollers.

2. In a machine of the class described, the combination of a frame, axles thereon, a roller mounted on the axles, a heater disposed within the roller and suspended on the axles, and adjustable doors carried by the axles and stationary with respect to the roller to control the draft through the latter.

3. In a machine of the class described, the combination of a frame, a roller having open ends and rotatably mounted in the frame, a heater within the roller, a plurality of door sections pivotally mounted at each end of the roller, a guard disposed over the upper portion of the rollers, and means on the sections of the door for adjustable engagement with the said guard for holding the door sections in different positions.

4. In a machine of the class described, the

combination of a frame, axles thereon, a roller supported by the axles, a fire-box in the roller and carried by the axle, and doors for the ends of the roller consisting of sections pivotally mounted on the axles.

5. In a machine of the class described, the combination of a frame, axles thereon, a roller supported by the axles, a fire-box in the roller and carried by the axle, doors for the ends of the roller consisting of sections pivotally mounted on the axles, a guard

mounted on the frame and disposed over the roller, and means on the sections of the doors for engagement with the guard for holding the door sections in different positions. 15

In testimony whereof I have signed my name to this specification in the presence of two subscribing witnesses.

AXEL WETTERVIK.
